CANDY BOX

Michel Schwartz, New York, N. Y.

Application December 26, 1950, Serial No. 13,567

Term of patent 3½ years

(Cl. D58—12)

To all whom it may concern:

Be it known that I, Michel Schwartz, a citizen of the United States and resident of New York, in the county of New York, State of New York, have invented a new, original, and ornamental Design for a Candy Box, of which the following is a specification, reference being had to the accompanying drawing, forming a part thereof, and of which:

Fig. 1 is a front perspective view of a candy box embodying my new design, showing the parts thereof in exploded position;

Fig. 2 is a front elevational view thereof, showing the parts in assembled position; and

Fig. 3 is a top plan view thereof.

The sides of the box not shown are identical with those shown.

I claim:

The ornamental design for a candy box, as shown and described.

MICHEL SCHWARTZ.
